UNITED STATES PATENT OFFICE.

GEORGE F. HARRISON, OF KNOXVILLE, TENNESSEE.

CALCULATING-MACHINE.

SPECIFICATION forming part of Letters Patent No. 701,721, dated June 3, 1902.

Application filed July 30, 1901. Serial No. 70,274. (No model.)

To all whom it may concern:

Be it known that I, GEORGE F. HARRISON, a resident of Knoxville, Tennessee, have invented a new and useful Improvement in 5 Calculating-Machines, which invention is fully set forth in the following specification.

My object is to provide a calculating-machine of simple, durable, and compact construction which will be positive and accurate in operation and which may be sold at a low price.

In calculating-machines heretofore devised having a series of rotatable numeral wheels or disks each representing a different order it has been common to separately move each wheel forward for the purpose of registering thereon, the wheels upon which no registry is being made remaining at rest.

The principal feature of my present invention resides in means whereby instead of operating upon this old principle I employ practically the reverse thereof—that is to say, the wheel upon which registry is to be made is held immovable, while the other wheels are moved backward together through a number of spaces directly corresponding to the number to be registered on the immovable wheel, then all of the wheels (including the one which was held immovable and upon which registry is to be made) are moved forward together through the same number of spaces as on the backward movement, the final result being a change in the position of the wheel which was at first held immovable corresponding to the number registered. By operating upon this new principle I am enabled to employ much simpler actuating mechanism than is commonly used in machines operating upon said old principle.

My invention also embraces mechanism for "carrying tens" from each wheel to the wheel representing the next highest order, as well as many other features of construction, all of which will be best understood by reference to the accompanying drawings, illustrating several of the many possible embodiments of my invention.

In said drawings, Figure 1 is a vertical sectional view on line *aa*, Fig. 2. Fig. 2 is a top plan view with part of the keyboard broken away and omitted to show the interior mechanism. Fig. 3 is a front elevation, part of

the casing being omitted to expose the interior mechanism. Fig. 4 is a longitudinal sectional view through the series of numeral-wheels on line *cc* of Fig. 5. Figs. 5 and 6 are detail sectional views on line *bb* of Fig. 4, the parts being shown in different positions in the two views. Fig. 7 is a detail view illustrative of the operation of the resetting mechanism for bringing the wheels to zero position. Fig. 7^a is a detail view of the means for rotating shaft 26. Fig. 8 is a perspective view of a smaller modified form of machine. Fig. 9 is a transverse sectional view of the 65 same. Fig. 10 is a bottom plan view with the cover on the under side omitted, and Fig. 11 is a longitudinal sectional view. Fig. 12 is a detail view illustrating modified pawl-and-ratchet mechanism.

1 is a suitable casing having a sight-opening 2, closed by a glass plate, through which the figures on the numeral-wheels are visible to the operator. Shaft 3, journaled at opposite ends in the sides of the casing, carries 75 loosely mounted thereon a series of numeral-wheels 4, on the peripheries of which are inscribed a cipher and the digits "1" to "9," inclusive, suitably spaced. Ratchet-wheels 5, splined on shaft 3 between the several 80 wheels, are engaged by pawls 6, pivoted to the left-hand sides of the wheels, respectively. Springs 7, also secured to the wheels, press the pawls into engagement with the ratchet-wheels 5 with sufficient friction to carry the 85 numeral-wheels with the ratchet-wheels during the backward rotation of shaft 3, unless said wheels or any one of them are or is positively held against such movement. Gear-wheels 8 and 9 are splined on shaft 3 at its 90 opposite ends. (See Fig. 4.) There is also splined on said shaft between gear-wheel 9 and the units numeral-wheel a disk 10, from which a rod 11 extends radially and then in a direction parallel to shaft 3 across the peripheries of all of the numeral-wheels to the outer end of an arm 12 on gear 8, to which arm it is secured. A series of ten equally-spaced pins 12 project from the right-hand sides of each numeral-wheel and are adapted 95 to be engaged by pawls 13, pivoted at 14 to the left-hand sides, respectively, of the several wheels 4. The wheel representing the highest order has no such pawl. The pawls

are normally held out of engagement with the pins by springs 15 pressing them against stops 16, and in this position elevations or humps 17 on the pawls project beyond the 5 peripheries of the numeral-wheels. The elevations 17 are adapted to be engaged by rod 11 to depress the pawls into engagement with pins 12 at the proper time to effect the carrying of tens from one wheel to the next, as 10 will be more fully explained hereinafter.

Fig. 5 shows the units-wheel 4 and parts coöperating therewith, the rod 11 resting behind the elevation 17 on pawl 13. To register "9" on the units-wheel, said wheel is held 15 against backward movement (as by means hereinafter explained) while shaft 3 is rotated in a backward direction (the direction indicated by arrow *x*, Fig. 5) through nine spaces, carrying all of the other numeral-wheels with 20 it. Then all of the numeral-wheels, including the units-wheel, are rotated forward (the direction indicated by arrow *y*, Fig. 5) through nine spaces, the units-wheel finally coming to rest in the position shown in Fig. 25 6, the rod 11 resting in front of elevation 17 of pawl 13. Now if three more are to be added to the units-wheel (and a total of "12" thus indicated at the sight-opening) said wheel is held while shaft 3 is rotated backward 30 a distance equal to three spaces. This backward movement of the shaft, and with it rod 11, from the position shown in Fig. 6 causes said rod to travel over the elevation 17, depressing pawl 13 on the units-wheel into engagement with one of the pins 12 on the tens-wheel and holding the latter while the shaft and rod travel a distance equal to the first of the three spaces, whereupon the rod having 35 passed over the elevation the pawl is released 40 and automatically disengaged from the pin on the tens-wheel, freeing the latter, so that it moves backward with the shaft through the second and third spaces. It will therefore be seen that the units-wheel (which was in the 45 "9" position) has made no backward movement, that the tens-wheel (which was in zero position) has moved backward through two spaces, and that the other wheels have moved backward three spaces. Shaft 3 and all of 50 the wheels are now moved forward three spaces, with the result that the units-wheel exhibits the numeral "2" and the tens-wheel the numeral "1" at the sight-opening. All of the other wheels exhibit zeros.

55 I will next describe the means for holding the numeral-wheels and for rotating shaft 3. The machine shown in Figs. 1 to 3 has eight numeral-wheels 4, and hence eight rows of keys 20. In each row are nine keys, numbered "1" to "9," respectively. Each key has a stem 21, Fig. 1, passing through an opening in the top plate 22 of the casing. Pins 23, passing through stems 21 beneath the plate, prevent removal of the keys. The key-stems 60 vary in length, according to the numerals on the keys, the stem of the "2" key being longer than that of the "1" key, and so on. Coiled

70
springs 24 about the key-stems bear at their lower ends upon the plate 22 and at their upper ends against washers 25, secured to the stems just below the key-heads. These springs act to normally hold the keys in and return them to the position shown in Figs. 1 and 3 while permitting them to be depressed by the operator.

75 26 is a shaft journaled in the ends of the casing. Coiled springs 27 are secured at one end to said shaft and at the other end to the underside of plate 22. Bars 30, one for each 80 row of keys, pivotally engage shaft 26 at their rear ends and are engaged by the forked lower ends of key-stems 21, as clearly shown in Fig. 1.

85 At each end of shaft 26 and rigidly secured thereto are arms 31 31, Fig. 1, having at their lower ends toothed segments 32, engaging the gear-wheels 8 and 9, respectively. Bars 33 and 34, extending across the interior of the casing, limit the upward and downward movement of the arms, and hence the rotation of 90 shaft 26, said arms being normally held against the upper bar 33 by the action of springs 27 upon the shaft. Flat springs 35, bearing against the under edges of bars 30, tend to normally hold the latter in the position shown in Fig. 1. In order to transmit to 95 shaft 26 the movement imparted to bars 30 by depression of the keys, each bar has a pin 36, Figs. 2 and 1, the ends of which project from 100 opposite sides of the bar and are adapted to engage two pins 37 37; but pins 36 do not bear against the pins 37 in the normal position of the parts. (See Figs. 1 and 7^a.) On the contrary, a slight downward movement of each 105 bar is required to bring its pin against the pins on the shaft. This preliminary movement effects the operation of means for locking the numeral-wheel (upon which registry is to be made) against backward rotation before the backward rotation of shaft 3 and the 110 other numeral-wheels begins.

I will next describe the means for thus locking any one of the numeral-wheels. Rod 40 extends from side to side of the casing in the front part thereof. A series of bifurcated 115 locking-arms 41, one for each numeral-wheel, pivotally engage and depend from rod 40. One side of the bifurcated arms 41 is longer than the other, its lower end 42 passing through and working in a slot 43 in a plate 120 44 and terminating in proximity to the pins 12 on the numeral-wheels. The front ends of bars 30 are adapted to move up and down in slots 48, Fig. 3, of the arms 41. A pin 49 on each bar 30 bearing against an inclined 125 part 45 on its corresponding arms 41 normally holds the latter in the position shown in full lines in Fig. 1, with its lower extremity 42 out of the path of the pins 12 on the numeral-wheel; but a spring 46, secured at one end 130 to bar 40 and at its other end bearing against a pin 47 on arm 41, acts to move the lower end of the latter to the dotted-line position, Fig. 1, and lock the numeral-wheel against back-

ward movement as soon as one of the keys is operated to depress bar 30 and move pin 44 away from incline 45.

The operation of the means for rotating the numeral-wheels shaft and the means for locking the appropriate numeral-wheel against backward rotation in registering three hundred, for example, is as follows: Depression of the "3" key in the third or hundreds row of keys 20 moves the corresponding bar 30 downward a distance corresponding to three spaces on the numeral-wheels. The preliminary movement of bar 30 before numeral-wheels shaft 3 begins to rotate carries pin 15 49 off of the incline 45 of locking-arm 41, permitting spring 46 to move the latter to the dotted-line position in Fig. 1, with its lower extremity 42 in the path of pins 12 on the hundreds numeral-wheel, thus locking the 20 latter against backward movement with the shaft 3. In its backward rotation shaft 3 carries with it all of the numeral-wheels except the hundreds-wheel, the pawl 6 on the latter rotating over three ratchet-teeth on its corresponding ratchet-wheel 5. The key being now released by the operator, spring 35 at once returns bar 30 to its normal position, returning arm 41 to its full-line position, Fig. 1, and springs 27, acting through shaft 26, elevate 25 arms 31 to their full-line position, Fig. 1. The upward movement of toothed segment 32 imparts a forward rotation to shaft 3, and consequently moves all of the numeral-wheels forward three spaces, the result being that 30 the numeral "3" on the hundreds-wheel and the zeros on all of the other wheels are exposed at the sight-opening. Any other number or numbers may then be registered on the wheels in the same manner, the sum-total 35 being finally exhibited at the sight-opening.

In order to return all of the numeral-wheels to their zero positions after registry has been made thereon, I provide the following means: One of the pins 12 is provided with a radial 40 extension or projection 60 adjacent to the right-hand face of the numeral-wheel, but so positioned as not to interfere with the engagement of pawl 13 on the adjacent numeral-wheel with the outer end of said pin, as clearly 45 shown in Fig. 7. A rod 61, journaled in the sides of the casing and extending through the interior thereof above the numeral-wheels and just beneath plate 44, has thereon a series of lugs 62, one for each numeral-wheel. 50 A weighted operating-lever 63 on the end of rod 61 outside of the casing acts to normally hold said rod in such position as to elevate lugs 62 out of the path of the projection 60 on pin 12, as clearly shown in Fig. 1. When 55 it is desired to reset the numeral-wheels to their zero positions, the operator manipulates arm 63 to lower lugs 62 to the position shown in Fig. 7 in the path of projections 60. Key 64, Fig. 2, is now depressed to give arms 31 60 a full downward stroke, and thus rotate shaft 3 through nine spaces. The result is that the numeral-wheels will rotate backwardly with

the shaft until they are stopped by the projections 60 on one of the pins 12 thereof coming in contact with its corresponding lug 62. 70 All of the numeral-wheels will thus be brought into alinement, so that upon the forward movement of the shaft the zeros on all the wheels will be exposed at the sight-opening.

It may be found desirable to prevent over-rotation of the several numeral-wheels on the forward movement of the shaft 3. For this purpose I provide the following mechanism: 75 70 is a shaft journaled in the sides of the casing beneath the numeral-wheels. From this shaft a series of stop-arms 71, one for each numeral-wheel, having their outer extremities bent upwardly and adapted when the arms are elevated to project into the path of pins 12 on the numeral-wheels respectively, 80 as shown in Fig. 1. A spring 72, secured at one end to the casing and at the other end to shaft 70, normally holds the stop-arms 71 in their lowermost position out of the path of pins 12. A depending arm 73 on gear-wheel 8 85 engages a lug 74 on shaft 70 when the shaft reaches the limit of its forward movement and rotates shaft 70 to elevate the stop-arms to the position shown in Fig. 1, thus arresting the numeral-wheels at their proper positions and preventing them from moving forward after rotation of shaft 3 has ceased. 95

Figs. 8 to 11 illustrate an embodiment of my invention in a machine of small size, which may be readily transported from place to place. 80 is a cylindrical casing having a plurality of sight-openings 81, one for each numeral-wheel. 82 is the numeral-wheel shaft, journaled at one end in a circular plate 83, which closes one end of the casing, and at its 100 other end in a plate 84, extending across the other end of the casing. 85 is a gear-wheel on the end of shaft 82 outside of the casing adjacent to the plate 83. 86 is a frame adapted to slide backward and forward on two 105 screws 87, the shanks of which pass through an elongated slot 88 in said frame and into plate 83. The lower edge of frame 86 is provided with a series of gear-teeth engaging the pinion 85, so that shaft 82 is rotated 110 by backward-and-forward movement of the frame. A plate 89, secured to the upper edge of the frame 86, bears along its outer edge in a row a "0" and the digits "1" to "9," arranged at equal intervals. A "0" 115 and the digits "1" to "9" are likewise disposed in a row along the inner edge of said plate, but in the reverse order. 90 represents a series of keys, the stems of which pass through a flange 91, depending from plate 89, 120 and into openings through the upper edge of plate 86. A coiled spring 97, secured at one end to the stem of the key and at its other end bearing against frame 86, acts to hold the keys in the position shown in full lines in Fig. 125 11. The keys are adapted, however, to be pushed into the position indicated in dotted lines in Fig. 11, thereby compressing springs 97 and causing the inner ends of their stems

to project into alinement with a stop-pin 92 on plate 83, thereby limiting the movement of frame 86 in one direction. 100 represents the numeral-wheels, loosely mounted on shaft 5 82 and having a series of ten pins 101 projecting from the right-hand face thereof. Ratchet-wheels 102 are secured to the shaft 82 between the numeral-wheels. 103 represents pawls, Fig. 12, one pivoted to each numeral-wheel 10 at 104 and having a tooth 105 pressed into engagement with the teeth of ratchet-wheel 102 by the action of a spring 106. The tooth 107 on the end of ratchet 103 is adapted to be pressed outwardly into engagement with one 15 of the pins 101 of the numeral-wheel by the action of enlarged tooth 108 on ratchet-wheel 102 for the purpose of carrying tens from one numeral-wheel to the next in a manner which will be readily understood from the fore- 20 going description of the carrying mechanism shown in Figs. 1 to 7. 110 is a spring secured at one end to shaft 82 and at its other end to a pin 111 on plate 84 and adapted to be wound up upon movement of frame 86 in the direction indicated by the arrow in Fig. 8, so that when said frame is released by the operator shaft 82 will be rotated in the reverse direction, returning the frame to the position shown in said figure. A plate 112 on shaft 82 ad- 25 jacent to spring 110 acts to hold the latter in position as it is wound up. 120 represents a series of keys, one for each numeral-wheel, each key consisting of a flat spring secured at one end to the casing 80 and at its free end 30 carrying a pin 121, projecting through a small opening in casing 80 and adapted when pressed inwardly against the tension of the spring to engage one of a series of ten openings 122, arranged equidistant about the periphery of 35 the corresponding numeral-wheel. Any numeral-wheel upon which registry is to be made may be thus held at rest during the backward movement of the shaft 82 and the other numeral-wheels through a number of spaces de- 40 termined by the particular key 90 which is at the same time pressed in by the operator. When frame 86 has been moved forward (rotating shaft 82 and the numeral-wheels backward) until the stem of the depressed key 90 45 strikes pin 92, the operator releases key 120, so that upon the return movement and the corresponding forward movement of the shaft 82 all of the numeral-wheels will move forward through the same number of spaces. 50 55 To prevent overrotation of the numeral-wheels upon their forward movement, I provide means similar to those already described with reference to Figs. 1 to 7. 130 is a shaft journaled in lugs 131 on the lower side of cas- 60 ing 80 and having stop-arms 132, one for each wheel, the outer ends of which project upwardly through openings in the casing. A bent arm 133 on shaft 130 extends upwardly through an opening in casing 80, and a pin 65 134, projecting from a disk 135, bears against arm 133 to elevate stop-arms 132 into the path of the pins on the numeral-wheels as soon as

frame 86 and shaft 82 reach their starting positions.

For resetting all of the numeral-wheels at 70 zero position each numeral-wheel has a pin 140 projecting from its periphery at proper position. 141, Fig. 11, is a plate adapted to be moved into the path of said pins through a slot in the under side of casing 80 by pressure upon a knob 142 and against the tension of springs 143, which act to normally hold said plate in the position shown in Fig. 11. By pressing upon knob 142 and giving frame 86 a full movement in the direction of arrow, Fig. 80 8, all of the wheels will be rotated until their pins 140 strike plate 141, bringing them all into alinement, so that upon their forward movement they will be brought to position to exhibit "0's" at the right openings. 85

150 is a cover secured to casing 80 over shaft 80, plate 141, and other parts.

What I claim is—

1. In a calculator or analogous machine, a series of numeral-wheels, means for collectively rotating said wheels in one direction and then in a reverse direction said means requiring all of the wheels to always move the same distance in one direction, and means for holding any wheel at rest while the others are 95 rotating in the other direction.

2. In a calculator or analogous machine, two or more numeral-wheels, means for rotating said wheels together in one direction and then in a reverse direction said means requiring both wheels to always move the same distance in one direction, and means for holding either of said wheels at rest while the other is rotating in the other direction. 100

3. In a calculator or analogous machine, a series of numeral-wheels adapted to be collectively but not separately or singly rotated in one direction and any one or more of which may be held at rest while the others are rotated in the opposite direction, means for rotating the wheels in opposite directions, and means requiring all of the wheels to always move the same distance in one direction, and means for holding any wheel at rest while the others are rotated in the other direction. 110

4. In a calculator or analogous machine, two or more numeral-wheels, means for rotating said wheels together in one direction and then in a reverse direction, means for holding the wheel representing the lower order at 120 rest while the other wheel is rotating in one of said directions, and automatically-operating means for carrying tens from one wheel to the other.

5. In a calculator or analogous machine, a series of numeral-wheels, means for collectively rotating said wheels in one direction and then in a reverse direction, means for holding any wheel at rest while the others are 125 rotating in one of said directions, and automatically-operating means for carrying tens from each wheel to that representing the next 130 higher order.

6. In a calculator or analogous machine, a

- series of numeral-wheels, a rotatable shaft on which said wheels are loosely mounted, connections between each wheel and the shaft requiring all of the wheels to move with the shaft when the latter is rotated in one direction but permitting any wheel to be held at rest while the shaft and other wheels are rotated in the reverse direction, means under control of the operator for rotating the shaft a desired distance in opposite directions and for holding any wheel at rest while the others are rotated in one of said directions.
7. In a calculator or analogous machine, a series of numeral-wheels, a rotatable shaft on which the wheels are loosely mounted, pawl-and-ratchet connections between each wheel and the shaft requiring all of the wheels to move with the shaft when the latter is rotated in one direction but permitting any wheel to be held at rest while the shaft and other wheels are rotated in the reverse direction, means under control of the operator for rotating the shaft a desired distance in opposite directions and for holding any wheel at rest while the others are rotated with the shaft in one of said directions.
8. In a calculator or analogous machine, two numeral-wheels, means under control of the operator for rotating said wheels together in one direction and for holding one wheel while the other is rotated in the opposite direction, pins on one wheel, a pawl on the other, and automatically-operating means for throwing the pawl into engagement with said pins to carry tens from one wheel to the other.
9. In a calculator or analogous machine, a series of numeral-wheels, a shaft upon which said wheels are loosely mounted, pawl-and-ratchet connections between each wheel and the shaft, means under control of the operator for rotating the shaft in opposite directions and for holding any wheel at rest during the rotation of the shaft in one direction, a series of pins projecting from each wheel, a pawl on each wheel adapted to engage the pin of an adjacent wheel, and automatically-operating means for throwing the pawls into engagement with the pins for carrying tens.
10. In a calculator or analogous machine, a series of numeral-wheels, a shaft upon which said wheels are loosely mounted, pawl-and-ratchet connections between each wheel and the shaft, means under control of the operator for rotating the shaft in opposite directions and for holding any wheel at rest during the rotation of the shaft in one direction, a series of pins projecting from each wheel, a pawl on each wheel adapted to engage the pins of an adjacent wheel and having a part projecting beyond the periphery of its wheel, a rod rigidly secured to the shaft and extending across the peripheries of the wheels and adapted by engagement with the projecting parts of the pawls to move the latter into engagement with the pins and auto-

matically carry tens from each wheel to that of the next higher order.

11. In a calculator or analogous machine, a series of numeral-wheels, a rotatable shaft upon which said wheels are loosely mounted, means for locking each wheel to the shaft as the latter rotates in one direction but permitting it to be held at rest while the shaft rotates in the other direction, means under control of the operator for rotating the shaft in opposite directions and for holding any wheel at rest while the shaft and other wheels rotate in said other direction, and means for resetting all of the wheels to a predetermined position.

12. In a calculator or analogous machine, a series of numeral-wheels, a rotatable shaft upon which said wheels are loosely mounted, means for locking each wheel to the shaft in the forward rotation of the latter but permitting it to be held at rest during the backward rotation of the shaft, means under control of the operator for rotating the shaft in opposite directions and for holding any wheel at rest during the backward rotation, and means under control of the operator for arresting all of the wheels in like positions on said backward rotation, whereby they are all reset at zero or other desired position.

13. In a calculator or analogous machine, a series of numeral-wheels, a shaft upon which they are loosely mounted, means locking each wheel to the shaft as the latter rotates in one direction but permitting it to be held at rest while the shaft rotates in the other direction, means under control of the operator for rotating the shaft in opposite directions any desired distance corresponding to the number to be registered on any wheel and for holding any wheel upon which registry is to be made at rest while the shaft and other wheels are rotated in said other direction.

14. In a calculator or analogous machine, a series of numeral-wheels, a shaft upon which they are loosely mounted, means locking each wheel to the shaft as the latter rotates in one direction but permitting it to be held at rest while the shaft rotates in the other direction, a series of keys for each wheel the several keys of each series being movable different distances corresponding to the number to be registered thereby on the numeral-wheel of its series, means actuated by the movement of any key for imparting a corresponding backward-and-forward rotation to the shaft, and means actuated by the movement of any key of a series to hold the numeral-wheel of that series at rest while the shaft rotates in said other direction.

15. In testimony whereof I have signed this specification in the presence of two subscribing witnesses.

GEO. F. HARRISON.
